HUMIDIFIER

Gerald W. Skilbeck, Kenosha, Wis.

Application July 18, 1936, Serial No. 91,300

7 Claims. (Cl. 237—78)

This invention relates to improvements in humidifiers and refers particularly to humidifiers to be used with steam heating or any other suitable source of steam.

5 In humidifiers of this type heretofore in use raw steam from the radiator passed directly into the atmosphere, or water was conducted directly from the radiator to an evaporator unit. While these past constructions did obtain a degree of 10 humidification, their capacity was limited and they had the further serious objection of obnoxious odors present in the steam emitted from the radiator. Also, where the units were supplied with water, objectionable lime deposits had 15 to be contended with.

With the above and other objections to past humidifiers in mind, this invention has as an object to provide a small compact humidifier capable of attachment to a steam radiator or other source of steam, and so designed that the vapor discharged therefrom into the atmosphere is the result of a distillation process which removes all 20 objectionable odors.

Another object of this invention is to provide a 25 humidifier having an exceptionally high evaporation with low pressures.

Another object of this invention is to provide a 30 humidifier which is entirely automatic in its operation and which is automatically supplied with water through the process of condensation from the radiator, and which is so designed as to become operative whenever the heat is on.

Another object of this invention is to provide a 35 humidifier with greater capacity than those heretofore in use, and at the same time to simplify the construction as to enable its manufacture at low cost.

Another object of this invention is to provide a 40 humidifier of the character described which is quiet in operation.

A further object of this invention is to provide a 45 humidifier which may be easily and quickly attached to any conventional steam radiator.

A still further object of this invention is to provide 50 vide means for adjusting the output of the humidifier.

With the above and other objects in view which 55 will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, 5 and in which:

Figure 1 is a front view of a conventional steam heating radiator illustrating the application of this invention thereto;

Figure 2 is an enlarged vertical section through 10 the humidifier per se;

Figure 3 is a sectional view taken through Figure 1 on the plane of the line 3—3; and

Figure 4 is a top plan view of the humidifier illustrating particularly its outlet port and adjusting screw.

Referring now more particularly to the accompanying drawing in which like numerals indicate like parts, the numeral 5 represents a conventional steam heating radiator which, as is customary, is composed of a plurality of vertical flanges joined at their upper and lower ends. At the top an inlet pipe 6 conducts the heating fluid into the radiator and at the bottom an outlet pipe 7 provides for the return of the condensate. 20 At one end of the radiator the humidifier of this invention, and indicated generally by the numeral 8, is mounted.

The humidifier proper comprises a vertical casing or receptacle consisting preferably of a cylindrical shell with its upper and lower ends closed by caps 10 and 11, respectively. The upper cap 10, which may be removable, has an outlet port 12 provided with a downwardly extending tube 13 to insure quiet operation. The lower cap 11 30 has an overflow pipe 14 secured thereto and extending up into the receptacle or casing to a point substantially medially of its ends to determine the level of water contained within the receptacle. The lower end of the overflow pipe 40 has a tube 15 attached thereto which leads to, and supports, an evaporator unit 16.

The evaporator unit 16 serves merely as an auxiliary humidifier, being supplied only with the 45 overflow of water from the humidifier receptacle. It consists of a plurality of sheets of bibulous material confined between screens and equipped with a trough 17 at the bottom thereof. An evaporator unit of this character is illustrated and described in detail in Patent No. 2,034,886, 50 issued to Gerald W. Skilbeck, March 24th, 1936.

Entering the interior of the receptacle through its side wall is a duct 18 adapted to conduct live steam from the radiator to a point below the level of the water contained within the receptacle to 55

boil the water and also replenish the supply and maintain the level constant as determined by the location of the top of the overflow pipe. This duct 18 may be of any suitable construction, and in 5 the present instance comprises an elbow 19 having a threaded nipple 20 projected through a hole in the side wall where it is secured by a nut 21. The threaded nipple is adapted for attachment to a tapped port 22 in the end wall of the radiator 10 whereby the duct is not only communicated with the interior of the radiator, but the entire unit is also physically supported from the radiator.

The other end of the elbow 19 has a T-fitting 23 secured thereto, to the stem of which a vertical 15 tube 24 is attached. The tube 24 extends down alongside the overflow pipe to a point adjacent the bottom of the receptacle and substantially below the top of the overflow pipe to locate the outlet for the live steam well below the water 20 level.

In the head of the T-fitting an adjusting screw 25 is threaded to provide means for limiting the free motion of a ball check valve 26 which serves 25 to close the duct passage against the admission of air into the radiator. The outer end of the adjusting screw 25, which is slotted for the reception of a screw driver, projects through a hole 27 in the cap 10 for convenient adjustment.

In operation steam flows from the radiator 30 through the duct 18 into the body of water contained within the receptacle and causes the same to boil. As the water boils the vapor rising therefrom is emitted through the opening 12. To preclude water from splashing out through the 35 opening 12 the entire receptacle except for the space occupied by the duct 18 and the overflow pipe, is filled with metal wool or some other suitable material. Obviously, the metal used for this purpose should be a non-ferrous metal, preferably copper.

When the unit is first set in operation it is desirable to fill it with water. Thereafter it is kept properly filled by the condensation of the steam conducted into the water from the radiator.

45 From the foregoing description taken in connection with the accompanying drawing, it will be readily apparent to those skilled in the art, that this invention provides an exceedingly simple but efficient humidifier which by reason of its simplicity of design can be manufactured at an exceptionally low cost, and also that by virtue of the fact that the steam from the heating radiator is not directly discharged into the atmosphere but is used merely to maintain the 50 supply of water and to boil the same so that the actual vapor discharged into the atmosphere is that produced as a result of a distillation process, no objectionable odors are produced in the operation of the humidifier.

60 What I claim as my invention is:

1. A humidifier for use with a steam radiator for discharging odorless steam vapor directly into the atmosphere comprising: a receptacle closed except for a discharge opening in its top; a continuously open overflow opening to the interior of the receptacle a short distance above the bottom thereof, the shape and dimensions of the receptacle being such that its portion disposed below the mouth of the overflow forms a small 65 reservoir for water; a steam inlet duct entering the receptacle and having its discharge end positioned beneath the mouth of the overflow to be submersed in the water so that live steam flowing through said inlet duct is discharged directly 70 into the water, said duct having an area so as to

admit a large volume of steam in proportion to the small amount of water contained within the receptacle so that the live steam violently boils the water in the receptacle and causes odorless steam vapors from the boiling water to issue 5 from the discharge opening in the top of the receptacle; a ball check valve in said steam inlet duct to be lifted off its seat by steam pressure as long as it exceeds atmospheric pressure and adapted to close upon a decrease in steam pressure below atmospheric; and means adjustable from the exterior of the receptacle for limiting the extent said ball may be lifted from its seat so that the flow of steam through said inlet may be controlled. 15

2. A humidifier of the character described comprising: an upright receptacle adapted to hold a supply of water and having end walls closing its top and bottom, the top wall being provided with a discharge opening, said receptacle 20 having a transverse dimension substantially less than its height; a constantly open overflow pipe leading from the receptacle with its mouth disposed at a height less than half the height of the receptacle to drain off excess water and 25 maintain a relatively small supply of water in the bottom of the receptacle; a steam inlet for discharging live steam into the receptacle below the water level to violently boil the water and cause steam vapors to issue from the discharge 30 opening in the top wall of the receptacle; and a check valve in said steam inlet above the water level open as long as the steam pressure is in excess of atmospheric and arranged to close when such pressure drops below atmospheric. 35

3. A humidifier of the character described comprising: a receptacle having a discharge opening in its top and having a constantly open overflow with its mouth on a level substantially no higher than half the height of the receptacle 40 to drain off water contained within the receptacle in excess of a predetermined small amount in the bottom thereof; a steam inlet open to discharge live steam into the receptacle below the water level to cause the water to boil violently 45 and discharge steam vapor through the opening in the top of the receptacle; and a metallic packing substantially filling the interior of the receptacle to prevent the water vapor produced by the violent boiling of the water from splashing 50 upwardly through the discharge opening.

4. A humidifier of the character described comprising: a receptacle having a discharge opening in its top and having a constantly open overflow with its mouth spaced from the bottom 55 thereof to drain off water contained within the receptacle in excess of a predetermined small amount in the bottom thereof; a steam inlet disposed above the water level and having its discharge terminating below the water level to inject 60 steam directly into the water to cause the water to boil violently and discharge steam vapor through the opening in the top of the receptacle; a metallic packing substantially filling the interior of the receptacle to prevent the water vapor produced by the violent boiling of the water 65 from splashing upwardly through the discharge opening; and a silencing tube extending downwardly from the discharge opening into the interior of the receptacle to silence the discharge 70 of steam vapor therefrom.

5. A humidifier of the character described comprising: an upright metal shell having a transverse dimension less than its length and having top and bottom walls, the top wall being 75

- provided with a discharge opening; a ball check valve positioned within the interior of the casing with its inlet disposed substantially medially of the top and bottom of the casing and its ball ar-
5 ranged to be lifted off its seat by steam pressure introduced beneath the ball; a duct extending from the outlet of the ball check valve to a point adjacent the bottom of the receptacle to be sub-
mersed in a supply of water to be maintained in
10 the bottom of the receptacle; a steam inlet opening through the side wall of the casing for con-
ducting steam into said inlet of the ball check valve for passage down into the water as long as the steam pressure is in excess of atmospheric;
15 and an unrestrictedly open overflow opening to the interior of the receptacle with its mouth located a short distance above the lower open end of said duct to drain off water in excess of a predetermined small amount so that the volume
20 of steam introduced into the water is large in proportion to the amount of water contained within the receptacle whereby violent boiling of the water results to insure the discharge of a large volume of steam vapor into the atmosphere
25 through the discharge opening at the top of the receptacle.
6. A humidifier of the character described comprising: an upright receptacle adapted to hold a supply of water, said receptacle having a discharge leading from its upper portion and having a transverse dimension substantially less
- than its height; a constantly open overflow pipe leading from the receptacle with its mouth dis-
posed at a height substantially no greater than half the height of the receptacle to drain off excess water and maintain a relatively small supply of water in the bottom of the receptacle; steam inlet means for discharging live steam into the receptacle below the water level to violently boil the water and cause steam vapor to issue from the discharge; and a check valve open as long as the steam pressure is in excess of at-
mospheric and arranged to close said steam inlet means when said pressure drops below at-
mospheric. 5
7. A humidifier of the character described 15 comprising: an upright receptacle adapted to hold a supply of water and having end walls closing its top and bottom, the top wall being pro-
vided with a discharge opening, said receptacle having a transverse dimension substantially less than its height; a constantly open overflow pipe 20 leading from the receptacle with its mouth dis-
posed at a height less than half the height of the receptacle to drain off excess water and main-
tain a relatively small supply of water in the bottom of the receptacle; and a steam inlet for 25 discharging live steam into the receptacle below the water level to violently boil the water and cause steam vapor to issue from the discharge opening in the top wall of the receptacle. 30
